Primary Examiner — Rosemary K Tarcza(74) *Attorney, Agent, or Firm* — Knobbe Martens Olson & Bear LLP(57) **CLAIM**

The ornamental design for a mobile battery charger, as shown and described in the Figures.

DESCRIPTION

FIG. 1 is a top view of the mobile battery charger with charging cables in a closed position;
 FIG. 2 is a left-hand-side view of the mobile battery charger with charging cables in the closed position;
 FIG. 3 is a front view of the mobile battery charger with charging cables in the closed position;
 FIG. 4 is a right-hand-side view of the mobile battery charger in closed position;
 FIG. 5 is a rear view of the mobile battery charger with charging cables in the closed position; and,
 FIG. 6 is a bottom view of the mobile battery charger with charging cables in the closed position.

1 Claim, 1 Drawing Sheet(56)
